BOTTLE

Alan B. Lowry, Canton, Mass., assignor to The Gillette Company, Boston, Mass., a corporation of Delaware

Filed May 18, 1964, Ser. No. 80,021

Term of patent 14 years

(Cl. D58—8)

FIG. 1

FIG. 3

FIG. 1 is a side elevational view partially broken away of a bottle, showing my new design;

FIG. 2 is a top plan view thereof; and

FIG. 3 is a bottom plan view thereof.

The design is characterized by an upwardly and inwardly tapered body portion terminated by a substantially flat inwardly stepped shoulder from which an upwardly and inwardly tapered neck and cap portion extends together with a reversely tapered base portion, the degree of taper of the body portion being substantially equal to that of the combined neck and cap portion, all as shown.

This application is a continuation-in-part of application Serial No. D73,596, filed February 18, 1963, now abandoned.

I claim:

The ornamental design for a bottle, substantially as shown and described.
